UNITED STATES PATENT OFFICE.

WILLIAM V. MOORE, OF NEW YORK, N. Y., ASSIGNOR OF ONE-HALF TO JOHN J. HARTIGAN, OF NEW YORK, N. Y.

IGNITION TESTER.

Application filed October 23, 1924. Serial No. 745,475.

To all whom it may concern:

Be it known that I, WILLIAM V. MOORE, a citizen of the United States, and a resident of the city of New York, borough of Manhattan, in the county and State of New York, have invented a new and Improved Ignition Tester, of which the following is a full, clear, and exact description.

This invention relates to ignition testers for internal combustion engines and particularly to an improved device to be used on an automobile.

The object of the invention is to provide an improved testing structure which may be positioned so that the control will be on the dashboard of the automobile or at some other convenient point, the control being so formed that any one cylinder may be tested.

Another object of the invention is to provide a tester in which a controlling switch structure is presented including a sliding contact associated with guiding means whereby the contact may be moved opposite coacting contacts connected to the respective plugs of the engine.

A still further object of the invention is to provide an ignition tester for internal combustion engines with a control which includes a sliding and rotating contact capable of being brought into active association with any of the spark plugs for testing the same.

In the accompanying drawing—

Figure 1 is a diagram illustrating certain wiring and controlling device embodying the invention.

Figure 2 is a plan view of a control or switch device embodying certain features of the invention.

Figure 3 is a rear view of the structure shown in Figure 2.

Figure 4 is a sectional view through Figure 2, approximately on line 4—4.

Figure 5 is a sectional view through Figure 3, approximately on line 5—5.

Figure 6 is a transverse sectional view through Figure 2, approximately on line 6—6.

Figure 7 is a fragmentary top plan view similar to the lower half of Figure 2 but showing a slightly modified construction.

Figure 8 is a transverse sectional view through Figure 7, approximately on line 8—8.

Referring to the accompanying drawing by numerals, 1 indicates an internal com-

bustion engine of any usual kind provided with a number of spark plugs 2 of any desired kind. Current is connected to one side of these spark plugs in the usual manner while the opposite side is connected through 60 suitable wires 3 with the respective contacts 4, 5, 6, 7, 8 and 9. These contacts and associated parts form a control structure 10, which structure also includes a face plate 11 of metal and a body 12 preferably of insulating material. A transparent window 13 is provided in back of the opening 14 in plate 11, said transparent window covering the various contacts 4 to 9 inclusive, as well as a shiftable contact 15. The shiftable 65 contact 15 is bent at 16 and extends upwardly through the slot 17 in plate 11, the upper end being adapted to receive a knob 18 of insulating material whereby the contact may be readily shifted. A spring 19 70 is provided for normally holding the collar 20, which is rigidly secured to the contact 15, against the plate 11. A loosely mounted washer 21 surrounds the contact 15 and is arranged between the plate 11 and spring 75 19 whereby the parts may be readily slid back and forth along the slot 17 and the contact may be also swung back and forth so as to be moved out of proximity with any of the contacts 4 to 9 as it is moved along the slot 17. By reason of this construction and arrangement, the spark plug of any cylinder may be readily tested by moving the contact 15 opposite the contact in the structure 10 80 which corresponds to the particular plug to 85 be tested.

For instance, if it is desired to test the plug in cylinder 5, the parts are arranged as shown in Figure 2 and when the spark occurs in the spark plug a second spark will 90 jump from contact 9 to contact 15. If this does not occur, it is proof that the spark plug has not functioned. By moving the contact 15 to the next contact or any other contacts between 4 to 9, the plugs associated therewith may be tested. The contact 15 may be moved downwardly while pointing toward the various contacts 4 to 9 or may be swung around so as to be parallel with the slot 17 and then move opposite the desired contact, after which, it may be turned to be brought into proximity thereto. In this way, the various plugs may be tested successively or any one plug tested independently. It will be noted that the spring 19 100 105 110

will substantially lock the contact 15 in any of its adjusted positions so that it will not accidentally come opposite any of the other parts.

5 In Figures 7 and 8, a slightly modified construction is shown wherein a contact 15' is provided secured to a block of metal 22 which loosely fits against the wall 23 and adjacent the bottom 24. As this block is

10 rectangular, it cannot rotate but may freely slide. This block is provided with a threaded extension 25 extending through

15 the slot 17 whereby the knob 18' may be applied readily thereto and the block slid back and forth as contact 15' comes opposite any of the contacts 4 to 9. In this form of the invention, the contact 15' cannot rotate or rock but must be brought successively past the various contacts 4 to 9.

20 What I claim is:—

1. In an ignition tester of the character described, a body, a plurality of contacts arranged in a row carried by said body, a grounded plate mounted on said body and provided with a slot parallel with said contacts, and an auxiliary contact slidingly mounted in said slot, said auxiliary contact engaging said plate and projecting toward the other contacts so that as it is moved

25 along the slot it may be brought successively into proximity to the other contacts.

2. In an ignition tester for internal combustion engines, a body, a plurality of con-

tacts arranged in a row, a grounded metallic plate carried by the body and provided with a slot extending parallel to said contacts, an auxiliary contact extending through said slot and then at right angles to a plane parallel with but spaced from the first mentioned contacts, and resilient means for locking said auxiliary contact at any point along said slot.

3. In an ignition tester for internal combustion engines, a plurality of contacts arranged in a straight line, a rotating and sliding contact co-acting therewith, means for guiding said rotating and sliding contact so that it may be moved to a position opposite any of the other contacts, and means for temporarily locking said sliding and rotating contact in different adjusted positions.

4. In an ignition tester of the character described, a body, a plurality of contacts arranged in a row carried by said body, a grounded contact plate mounted on said body and extending parallel with said contacts, and an auxiliary contact slidingly mounted on said grounded plate, said auxiliary contact engaging said plate and projecting toward the other contacts so that as it is moved along the plate it may be brought successively into proximity to the other contacts.

WILLIAM V. MOORE.
